HUB CAP

Alan D. Foster, Adrian, Mich.
(P.O. Box 1022, Dayton, Ohio 45401)
Filed June 12, 1969, Ser. No. 17,667

Term of patent 14 years

Int. Cl. D12—14

U.S. Cl. D14—30

FIG-1

FIG-4

FIG. 1 is a perspective view of a hub cap showing my new design;

FIG. 2 is a top view thereof;

FIG. 3 is a bottom view thereof; and

FIG. 4 is a side view thereof.

I claim:

The ornamental design of a hub cap, substantially as shown.
